Patented Apr. 24, 1917.

UNITED STATES PATENT OFFICE.

EMIL C. LOETSCHER, OF DUBUQUE, IOWA.

REFRIGERATING APPARATUS.

1,223,813.

Specification of Letters Patent. Patented Apr. 24, 1917.

Application filed March 24, 1915. Serial No. 16,551.

To all whom it may concern:

Be it known that I, EMIL C. LOETSCHER, a citizen of the United States, residing at Dubuque, in the county of Dubuque and 5 State of Iowa, have invented certain new and useful Improvements in Refrigerating Apparatus, of which the following is a specification.

The principal object of my invention is 10 to provide an automatic control in refrigerating apparatus of the character described whereby the heating agent may be alternately applied and cut off during each cycle of operation.

15 Another object of the invention is to provide automatic means whereby the process of absorption is terminated at a predetermined point in the cycle of operation in order that the effectiveness of the machine is 20 not impaired by the absorption process continuing beyond a certain point.

Still another object of the invention resides in providing automatic means entering into the control of the apparatus and 25 operated by the temperature in the refrigerator member whereby the temperature in the refrigerator will not rise above a certain predetermined point.

Invention further resides in the conjoint 30 operation of the individual controlling means whereby the efficiency and effectiveness of the apparatus is materially increased over apparatuses of similar character.

Having now described the broad objects 35 of my invention, I will proceed to point out the mechanism by means of which the broad objects of my invention are accomplished.

Figure 1 is a side elevational view of my 40 improved refrigerating apparatus with parts in section.

Fig. 2 is a side elevational view of the gas valve plunger.

Fig. 3 is a longitudinal sectional view of one of the thermostatic members.

45 Fig. 4 is a sectional view of the line 4—4 of Fig. 3.

Fig. 5 is an end view of Fig. 3.

Fig. 6 is a sectional view of the gas valve.

Referring now more particularly to the 50 drawing, the generator-absorber 10 is of the horizontal type and is provided with a vapor conveying member 11 which extends upwardly from the generator-absorber and is then bent upon itself with its discharge end 55 entering the equalizing member 12.

An absorption pipe 13 disposed near the bottom of the generator-absorber is connected to the equalizing member by the extension pipe 14, the upper end of the extension pipe 14 projects beyond the lower end of 60 the vapor conveying member 11 so as to form an overflow pipe for the liquid in the equalizing member; the normal level of the liquid being indicated at B and which pipe maintains a uniform height of liquid within 65 the equalizing member.

A rectifying coil 15 has one end in communication with the equalizing chamber 12 with the coils thereof located within a condensing tank 16. 70

Within the generator-absorber is a cooling coil 17 to the upper end of which is connected an elbow 18 which enters the condensing tank and the upper end 19 of which is located at a point slightly below the highest overflow level indicated at 19^A of the condensing tank. A check valve 20 is preferably located in the pipe 17 to prevent return flow to the condensing tank. A cooling medium, such as water, is supplied to 80 tank 16 by means of a water supply pipe 16^A preferably discharging at the bottom of the tank. 75

The condensing chamber 21 is constructed 85 preferably of a seamless shell provided with a single inlet and outlet communicating member 22 terminating at the bottom of the condensing chamber 21 and provided with a plurality of perforations 23. The refrigerating member 24 consists essentially of a 90 seamless receiving vessel 25 to which a refrigerating coil 26 is connected having both of its ends in communication with the chamber 24. Surrounding the receiving vessel 25 is insulating material 27 which material 95 is held in place by a jacket 28.

A brine tank 29 is located within the ice chamber 30 of an ordinary refrigerator 31 and the refrigerating coil 26 is located 100 within the brine tank 29. Within the receiving vessel 25 is an enlarged pipe 32 surrounding one of the terminal ends of the coil 26 and terminating below the top of the vessel 25.

The pipe 33 or refrigerant conveying 105 member which is in communication with the rectifying coil 15 has one of its ends passing through the receiving vessel 25 and into the enlarged pipe 32 discharging at a point near the upper end of said pipe 32. A suitable 110

valve 34 is employed for the purpose of charging the apparatus with the refrigerating solution.

Within the generator-absorber 10 is a thermostatic member 35, shown in detail in Figs. 3, 4 and 5. This thermostat consists of a shell 36 within which is a shell 37 provided with bearing head 38 for supporting the shaft 39. The inner end of the shaft 39 carries a spiral member 40 which is preferably a strip of thermostatic material consisting of two metals having different coefficients of expansion. One end of the thermostatic metal is fastened to the shell 36 and the other end to the shaft 39 whereby a rise in temperature will cause the shaft 39 to rotate in one direction and a fall in temperature will cause a reverse rotation.

An arm 41 is secured to the shaft 39 but insulated therefrom and is provided with a forked end 42. A gas valve 43, shown in detail in Fig. 6, is connected to the gas supply pipe 44 and has a gas outlet pipe 45 also connected thereto.

A diaphragm 46 is suitably mounted within the valve which diaphragm carries a valve seat 47 co-operating with the seat 48 formed integral with the valve casing.

A spring 49 normally holds the valve open by forcing the diaphragm upward. A plunger 50 has its lower end in contact with the diaphragm and its upper end projecting beyond the valve casing. A solenoid magnet 51 is mounted directly over the center of the plunger 50 of the gas valve 43 and in axial alignment therewith. The plunger 52 of the solenoid is provided with a groove 53 into which groove a locking pin 54 is adapted to project for locking the plunger 52 in its upper position.

The locking pin 54 is suitably mounted in bearing blocks 55 attached to any convenient point upon the frame of the machine, whereby the locking pin is held in proper relation to the plunger 52 and arm 41.

Mounted upon the locking pin 54 are two disks 56 and 57, upon opposite sides of the fork 42 on the arm 41. The disk 56 is preferably made of insulating material such as fiber and is provided with a metal disk 58 secured thereto but insulated from the locking pin 54. Disk 57 is made of fiber or other insulating material.

A spring 59 holds the locking pin in engagement with the plunger 52 and also forces disk 58 away from contact point 60 for a purpose to be hereinafter described. The plunger 52 of the solenoid extends through the winding and is provided with an extension 61 to which a weight 62 is attached.

A supporting bracket 63 is suitably connected to the frame and has a lever 64 connected to it at its upper end. One end of the lever is pivotally connected to the weight

62 by means of the link 64^A. A sleeve 65 is suspended from the other end of the link 64 by a link 65^A. The overflow tube 66, having its intake end within the tank 16, is controlled by longitudinal movement of the sleeve 65 relative to the tube 66 since the tube 65 has a telescopic engagement with the end of the tube 66, thus lengthening or shortening the intake end of the tube according to the movement of the sleeve 65.

The overflow tube connects to the pipe or fitting 67 leading to the trap 68 and from the trap to the sewer through the pipe 69.

Referring now to the refrigerating member designated as 24, an extension tube 70 is suitably secured to the shell 25 and is provided with an elbow or extension 71 around which are one or more convolutions of a thermostatic metal 72 which thermostatic metal is electrically insulated from the elbow 71. Within the tube 70 is a circulating tube 73 provided with a funnel shaped opening 74, the funnel end of which terminates within the chamber 24 and its other end at the closed end of the tube 70. The function of the tubes 70 and 73 is to maintain a circulation of the refrigerant within both of said tubes until all of the liquid in the chamber 24 has been evaporated. The cone 74 traps some of the gaseous refrigerant and thus forces some of the liquid refrigerant contained in the tube 73 against the force of gravity into the tube 70 and extension 71 where it evaporates causing the thermostat to deflect due to the lowering of temperature produced by the evaporating refrigerant. Another thermostat 75 is placed within the refrigerator. This thermostat comprises a section of thermostatic metal 76 and a contact screw 77 to open and close the electric circuit at a predetermined temperature. The three thermostatic members, namely, 35, 72 and 75 are connected in series shown by wires 78, 79, 80 and 81 to a battery or other source of electrical energy 82. The winding of the solenoid 51 is also connected in series with the thermostats.

A gas supply pipe 44 leads to the gas valve 43 and the gas outlet pipe 45 has a burner 83 that is located below the generator-absorber. A by-pass pipe 84 serves to keep the pilot light burning whenever the main burner is shut off.

The operation of the machine will now be described in detail. Assuming that the generator-absorber 10 has been charged with a suitable quantity of a refrigerating medium, such as aqua ammonia of suitable strength, to the level indicated at (a), Fig. 1, and that the chamber 12 has been filled to the level indicated at (b), Fig. 1, by means of the charging valve 34. And it being further assumed that the pilot light at the end of the pipe 84 has been lighted and that the cooling medium has filled the condensing

tank 16 and also that the battery 82 has been connected as indicated, and all the thermostats 35, 72 and 75 have been properly adjusted. The electrical energy from the battery 82 will now flow through the solenoid 51 moving the plunger 52 upwardly thereby opening the valve and allowing the gas in the pipe 44 to flow to the burner 83. The upward movement of the plunger 52 simultaneously lowers the sleeve 35 to the position shown in Fig. 1, which lowers the level of the liquid in the condensing tank 16 to the lower level as indicated upon the drawing. Thus the water in the condensing tank 16 cannot pass into the intake end 19 of the pipe 18 as the water will flow over the upper end of the sleeve 65 and into the pipe 66. When the generator-absorber 10 becomes heated the gaseous vapor arising from the liquid therein passes through the pipe 11 and bubbles up through the liquid surrounding the discharge end of said pipe. A small quantity of liquid is carried through the pipe 11 with the vapor 25 which maintains the liquid level in the chamber 12 and any excess liquid flows back into the generator-absorber through the pipe 14. It is essential that the liquid level in the chamber 12 be maintained as will 30 later appear.

The pipe 11 serves to equalize the pressure in the generator-absorber 10, and the chamber 12, except for the very slight liquid pressure which must be overcome due 35 to the pipe 11 dipping into the liquid in the chamber 12. The tendency of the liquid in the generator to be forced up into the pipe 14 and thence into the chamber 12 and subsequently into the rectifying coil 15 is 40 thus entirely overcome owing to the pressure equalizing action of the tube 11. The vapor now passes through the rectifying coil 15 at which point any entrained water vapor is condensed. The water resulting 45 from this condensation flows back into the chamber 12 and thus further serves to maintain the liquid level therein and automatically supplying any loss by evaporation.

The gaseous vapor, now free from water, 50 passes through valve 34 and pipe 33 into the refrigerating chamber 24 wherein it generates a pressure not only in the chamber 24 but in the coil 26 as well. The gaseous vapor next passes through the pipe 22 and 55 out through the openings 23 into the condensing chamber 21. As the solution in the generator-absorber becomes weaker its temperature gradually rises and as a consequence the arm 41 slowly moves to the right 60 as indicated by the dotted lines. The forked end 42 of the arm 41 now engages disk 57 moving the locking pin 54 whereupon the plunger 52 drops by gravity upon the plunger 50 of the gas valve. The disk 57 is set 65 at a point whereby the arm 41 will not come

in contact with the same until the solution in the generator-absorber has been weakened to a predetermined point as indicated by its temperature. As the plunger 52 falls upon the plunger 50 the gas valve is closed 70 and at the same time sleeve 65 is raised which in turn raises the overflow level in the condensing tank 16 to the level indicated at 19^a. As a result the water now flows through the pipe 18 to the coil 17 75 which is positioned within the generator-absorber, thus cooling the liquid within the generator and causing a reduction of pressure therein. The same reduction in pressure takes place in the chamber 12 and in 80 the refrigerating chamber 24. As the pressure in the generator-absorber is reduced the liquid in the chamber 12 is forced up pipe 11 to the point indicated at (c) which will be sufficiently high to force the returning 85 gas into pipe 14 and through the perforations in the absorption pipe 13 causing the returning gas to be absorbed by the liquid in the generator-absorber.

When the pressure in the generator-absorber has been reduced sufficiently, the pressure existing over the liquid anhydrous ammonia in the condensing chamber 21 will cause it to flow upward out of the condenser against gravity through the pipe 22 and to 90 be deposited in the chamber 24 and coil 26 filling said chamber 24 to a level as indicated at (d). A further reduction in pressure causes the ammonia in chamber 24 and coil 26 to evaporate lowering its temperature and producing the desired refrigeration within the chamber 30 of the refrigerator. 95

As the temperature within the generator-absorber is lowered, the thermostat designated as a whole at 35 and located within the generator-absorber, will cause the arm 41 to move toward the left until it contacts with the disk 58. This disk has previously been brought into contact with contact point 105 60 and is held in such contact by the falling of plunger 52 which thus prevents locking pin 54 from moving to the left until the plunger 52 is raised. The contacting of arm 41 with the disk 58, which closes the circuit 110 through the solenoid, will not cause the electrical energy to flow through it unless the other thermostat 72 and 75 are also closed. During the interval that the arm 41 has been moved to the left, thermostat 72 keeps the 115 circuit open for the lowered temperature produced in the extension arm 71 causes thermostat 72 to recede from its contact point 71^a, thus preventing the actuation of the solenoid. 120

The extension tube 70 will remain cold as long as there is any liquid ammonia to be evaporated therein. In order to keep the extension tube 70 cold until all the ammonia within the chamber 24 has evaporated, I 130

employ the circulating tube 73, which is provided with an inverted funnel end 74 to elevate the ammonia liquid by means of its own evaporation.

5 It is desirable, however, to terminate the process of evaporation or cooling when the coil 26 of the refrigerating member is substantially full of liquid. Under such conditions the coil 26 cannot act as a condensing 10 coil while the generating process is going on. Whatever condensation might take place in the coil when it is emptied during each cycle would warm up the surrounding brine, thus counteracting the previously produced 15 refrigerating effect and appreciably lowering the efficiency of the apparatus.

Assuming now that all of the ammonia in the chamber 24 has been evaporated and that the extension tube 70 begins to thaw or 20 warm up due to the temperature of the surrounding air, the thermostat 72 moves into contact with contact point 71^a. The solenoid 51 still will not be energized until the thermostat 75 is also closed, which will be 25 the case if such thermostat is set to open at a lower temperature than the temperature of the chamber in which it is located. If, however, the temperature of the chamber 30 is lower than the desired temperature for 30 which the thermostat is set, the latter will hold the circuit open until the temperature within the chamber 30 rises to the predetermined point at which the thermostat is set.

When the circuit is closed by the thermostatic metal 76 coming in contact with contact point 77, all contacts are thus closed and the electrical energy from the battery 82 now flows through the solenoid 51, causing plunger 52 to rise. As soon as plunger 40 50 is relieved of the pressure from plunger 52, the diaphragm 46 is moved upwardly by the spring 49, thus opening the gas valve and a new cycle of operation is started. As soon as the plunger 52 rises, the locking pin 45 54 is forced into the groove 53 thus holding the plunger 52 away from the plunger 50 and keeping the gas valve open. With the movement of the locking pin 54 to the left, the electrical circuit is broken at contact 50 50 point 60, thus deenergizing the solenoid 51 and relieving the battery. It will be seen that the current is thus of momentary duration and may be readily supplied by ordinary dry cells.

55 It is evident from the above description that I have provided means whereby a given temperature is maintained in the refrigerator and in addition to this salient feature I have provided means whereby the 60 cycle of absorption may be begun and also may be terminated at a predetermined point, both of which are essential to an automatic machine of this character.

It sometimes happens that a small quantity of water may be carried over with the

ammonia gas from the rectifier to the condenser thus lowering the quality of the ammonia and impairing the efficiency of the apparatus. I have provided simple automatic means for removing any such water 70 as follows:

When the machine is operating normally the anhydrous ammonia from the condenser will fill the chamber 24 to the level indicated at (d). Assuming now, that for some 75 reason, in case there is too small a quantity of cooling water over the rectifier, a small quantity of aqueous vapor passes over with the ammonia to the condenser. When this ammonia is transferred to the chamber 24 80 the latter will be filled to the level indicated at (e). Assuming also, that the previous operation had likewise carried over a slight quantity of water, it is obvious, that when the evaporation is terminated, a comparatively 85 large percentage of water will be contained in the liquid remaining in coil 26, which would continually increase until the tendency for the water to accumulate would seriously affect the operation of the 90 apparatus if not removed. The fresh charge of nearly anhydrous ammonia coming from the condenser through pipe 22 will be deposited in chamber 24 and thus force practically all of the liquid in the coil 26 downward and then upward into tube 32, until the level has been reached in chamber 24 and in tube 32. Inasmuch as the liquid 95 cannot get out through tube 22 and as its only exit is through tube 33 and thence 100 through the rectifier back to the generator-absorber, it is clear that by varying the size of tube 32, and the location of the end of tube 33, any predetermined amount of watery ammonia may be removed from the 105 refrigerating member and returned to the generator-absorber, even against the force of gravity.

Having now described my invention in detail, I will proceed to point out the novel 110 features which I claim as my invention.

I claim—

1. In refrigerating apparatus of the absorption type, the combination therewith of heat controlling means for applying and 115 shutting off the heating agent and thermostatic means separately operable from the heat controlling means but connected therewith whereby the heat controlling means is rendered operative or inoperative by said 120 thermostatic means.

2. In refrigerating apparatus of the absorption type comprising a generator, an absorber, a condenser and a refrigerating member, the combination therewith of 125 means for heating said generator, thermostatic means for controlling the heating agent operated by the temperature of said generator and thermostatic means for controlling the operation of the heating agent 130

thermostatic means and operated by the temperature of said refrigerating member.

3. In refrigerating apparatus of the absorption type comprising a generator, an absorber, a condenser and a refrigerating member, the combination therewith of means for heating said generator, thermostatic means for controlling the heating agent operated by the temperature of said generator and thermostatic means for controlling the operation of the heating agent thermostatic means and operated by the temperature of the apparatus at a point near the refrigerating member.
- 15 4. In refrigerating apparatus of the absorption type comprising a generator, an absorber, a condenser, a refrigerating member and a refrigerator, the combination therewith of means for heating said generator, thermostatic means for controlling the heating agent operated by the temperature of said generator, thermostatic means for controlling the operation of the heating agent thermostatic means and operated by the temperature of said refrigerating member and thermostatic means in said refrigerator operated by the temperature therein and controlling the operation of said heat controlling and refrigerating thermostatic means.
- 25 5. In refrigerating apparatus of the absorption type comprising a generator, an absorber, a condenser, a refrigerating member and a refrigerator, the combination therewith of thermostatic means in said
- generator, thermostatic means in said refrigerating member and thermostatic means in said refrigerator and means whereby the operation of the heat controlling thermostat in said generator is controlled by the conjoint operation of the thermostats in said refrigerating member and said refrigerator.
- 35 6. In refrigerating apparatus of the absorption type comprising a generator, an absorber, a condenser, a refrigerating member and a refrigerator, the combination therewith of thermostatic means in said generator, thermostatic means in said refrigerating member and thermostatic means in said refrigerator and means whereby the operation of the heat controlling thermostat in said generator is controlled by the conjoint operation of the thermostats in said refrigerating member and said refrigerator, said thermostats operating at different intervals.
- 45 7. In refrigerating apparatus of the absorption type comprising a generator, an absorber, a condenser, a condensing tank and a refrigerating member, of means for heating said generator, a heat controlling member and water controlling means in said condenser tank actuated by said heat controlling member.
